UNITED STATES PATENT OFFICE

164,365

TABLE

John Hiebert, Hillsboro, Kans.

Application March 20, 1951, Serial No. 14,554

Term of patent 7 years

(Cl. D33—14)

To all whom it may concern:

Be it known that I, John Hiebert, a citizen of the United States, residing at Hillsboro, in the county of Marion and State of Kansas, have invented a new, original, and ornamental Design for a Table, of which the following is a specification, reference being had to the accompanying drawing, forming part thereof.

I claim:

The ornamental design for a table, as shown and described.

JOHN HIEBERT.
